METHOD OF MAKING A BUFFING WHEEL
Anthony De Nuke, R.R. 3, Bothwell, Ontario, Canada
Filed Feb. 20, 1961, Ser. No. 90,435
6 Claims. (Cl. 51—293)

This invention relates to new and useful improvements in buffing wheels.

At present there are several types of buffs manufactured, and known. One type is a helically wound strip of material doubled up widthwise and wound around a hub. Another type uses a plurality of pre-pleated material wound around a hub and extending radially outward. Another discloses a strip of fabric cut in pieces on the bias and mounted on an axle.

The present invention relates to an improvement in the manufacture of buffs.

The main object is to provide a method of making buffs that is durable, inexpensive to manufacture, and simple in construction.

Another object is to provide a buff that is actually a combination buff in that is there is one buff inside the other.

Another object is to provide a buff that is formed to contain a buffing compound between the overlapping folds of the buff.

Due to the way the cloth for the buff is cut and wound a buffing compound, for example, tripoli, in liquid form may be brushed on the pleated strips of cloth forming the buff. The pleats of cloth and the rounds of stitching used in making the buff act as pockets and hold the buffing compound till each round of stitching is wore through when the buff is in use. As each round of thread is wore through more buffing compound is forced out by centrifugal action. Upon testing it was discovered that enough buffing compound can be inserted to last the life of the buff. If tripoli is used as the buffing compound the buffs should be used up in a reasonable length of time, or should be stored in a cool and dry room.

The buffs can be made with all new cotton or entirely from used and discarded buffs. Due to their construction and flexibility they are excellent for buffing odd shaped, grooved, ribbed and concaved castings and aluminum moldings and similar pieces. On most jobs today they will outwear the buffs at present on the market. The cost of material and the labor used in their manufacture is relatively very low.

Huge quantities of used buffs are purchased at scrap prices. From these the cotton, outside ring and steel centers are recovered for reuse in making the buffs of the present invention. Due to the difference in price between the buff made of new cotton and the rebuilt buff most of the customers prefer the rebuilt buff.

The cost of machinery and tools to manufacture the buffs is very low as the buffs are made on flat steel rings or forms, 10 gauge. The forms are used over and over for an unlimited number of times. The machines, jigs and fixtures, other than sewing machine and cloth cutter, can be made right in the shop where the buffs are manufactured, with very little material and cost, taking into consideration that all sizes and types, from 3 inches to 22 inches, of buffs are to be made.

The invention consists in the novel arrangements, combinations and construction of parts hereinafter described and shown in the drawings;

FIGURE 1 is a plan view of one form of the buff partly disassembled.

FIGURE 2 is a view of part of the strips being wound to form the buff in FIGURE 1.

FIGURE 3 is a plan view of another form of the buff disassembled partly.

2

FIGURE 4 is a view of part of the cloth being wound to form the buff in FIGURE 3.

FIGURE 5 is a plan view of another form of the buff partly disassembled.

5 FIGURE 6 is a plan view of another form of the buff partly disassembled.

Referring to the drawings, particularly to FIGURES 1 and 2, it will be seen that the buff comprises a center ring 1 shown in dotted lines in FIGURE 1 and formed of suitable material, preferably steel. Overlapping strips 2 extend outwardly on the bias and are passed around the center ring 1 to whatever diameter the buff is desired to be made. The buff may be made with as many layers of the overlapping material as desired. The strips 2 are sewn together helically as shown in FIGURE 1.

The method of manufacturing the buff shown in FIGURES 1 and 2 is by using a flat circular form of the diameter of the buff desired, placing spacer hooks between the outer flat form and the center ring 1, winding a long

10 strip of tape that has been impregnated with buffing compound, for example tripoli, around both the ring 1 and the flat form in a biased overlapping manner as shown in FIGURE 1 to the desired thickness. The strips are then 15 stitched together as shown at 3, the strips of tape cut around the outer edge 4 and the flat form removed for further use.

The above type of buff is excellent for all around buffing, will not rip or snag, wraps around and over rough castings and is excellent for automatic or pushup type 20 of buffing machines. It will hold more buffing compound than any other type of buff.

Referring to FIGURES 3 and 4 there is shown another type of construction of the buff. The inner layers are formed of sheets of cloth 5 passed around the center ring

25 1 to whatever thickness of buff is desired. Overlapping strips of cloth 6 extend outwardly on the bias over the inner layers 5. The inner layers 5 and the outer strips of cloth 6 are impregnated with buffing compound before being placed in position. The layers 5 and 6 are sewn together helically from the center ring 1 to the necessary distance from the outer edge.

The buff shown in FIGURES 3 and 4 is manufactured similar to that shown in FIGURES 1 and 2, by using a flat circular form, spacing hooks between the flat form 45 and the center ring 1, winding the buffing compound impregnated cloth 5 around the ring and form to the necessary thickness, winding the buffing compound impregnated strips of tape 6 on the bias over the cloth 5, sewing helically the cloth and the tape from the center ring 1 to the inner circumference of the flat form, cutting the cloth 5 and the tape 6 at the outer edge, and withdrawing the flat form.

The type of buff shown in FIGURES 3 and 4 is used for hard all around buffing on steel, aluminum, brass, copper or chrome. The cloth threads on this buff run in so many different directions that extra wear is obtained. The rounds of stitching 7 and the size of thread used determines the stiffness of this type of buff.

Referring to FIGURE 5 there is shown another type 60 of buff which is structurally the reverse to that shown in FIGURE 3, in that the inner strips of cloth 8 extend outwardly on the bias to the diameter of buff desired, and the outer layers 9 are formed of sheets of cloth extending outwardly over the inner strips of cloth 8.

65 This form of buff in FIGURE 5 is used for soft and medium polishing and can be sewn to the outer edge to stiffen the buff.

Referring to FIGURE 6 there is shown another type 70 of buff in which the inner layers are formed of strips of cloth 10 extending outwardly on the bias to the desired diameter of the buff and flat sheets of cloth 11 covering

the strips of cloth 10. If it is helically sewn together with the stitching $\frac{1}{4}$ inch apart it makes an extra hard buff. It can be used for hard and fast cutting.

In the construction of the modifications of the buff above described the buffering compound, for example, tripoli, is added to the cloth, and then when the cloth is sewn to the flat form and the inner ring, and due to the construction of the buff is self feeding due to the centrifugal force produced.

While the invention has been shown and described with particular reference to specific embodiments, it is understood it is not to be limited thereto but is to be construed broadly and limited only by the scope of the claims.

The embodiments of the invention in which an exclusive property or privilege is claimed are defined as follows:

1. A method of making a buffering wheel comprising the steps of successively winding a plurality of layers of fabric around an inner ring and spaced outer circular form concentric to said ring to form a laminated fabric disk with some of the layers disposed with the threads on a bias to the threads of the other layers, sewing the layers of fabric together by a helical row of stitching between the ring and outer form, cutting the layers of fabric along the outer edge and removing the outer form.

2. A method of making a buffering wheel as described in claim 1 including the step of impregnating the layers of fabric with a buffering compound.

3. A method of making a buffering wheel comprising the steps of winding a fabric around an inner ring and spaced

concentric outer circular form to form a plurality of fabric layers, winding a strip of fabric around said ring and form obliquely to the radius of the ring with the edges of the strip in lapped relation, sewing the layers and strip of fabric together by a row of stitching between the ring and form, cutting the layers of fabric and strips of fabric around the outer edge of the form and then removing the form.

4. A method of making a buffering wheel as described in claim 3 wherein the layers of fabric are formed with pleats to form spaced laps.

5. A method of making a buffering wheel comprising the steps of winding a strip of fabric around an inner ring and spaced concentric circular form with the edges of the strip overlapped, winding a fabric around the inner ring and circular form to form layers of fabric in superimposed relation to the wound strip of fabric, sewing the fabric strip and layers of fabric together, cutting the strip and layers of material along the outer edge of said form and then removing the form.

6. A method as described in claim 5 wherein the layers of fabric are pleated to form spaced overlaps.
